UNITED STATES PATENT OFFICE.

FRANCES B. MERRILL, OF JONESPOINT, NEW YORK, ASSIGNOR TO
MERRILL PROCESS COMPANY, A CORPORATION OF NEW YORK.

STILL.

SPECIFICATION forming part of Letters Patent No. 761,315, dated May 31, 1904.

Application filed April 7, 1903. Serial No. 151,472. (No model.)

To all whom it may concern:

Be it known that I, FRANCES B. MERRILL, of Jonespoint, county of Rockland, and State of New York, have invented a new and useful Improvement in Stills, of which the following is a specification.

My invention has reference to a still designed with special reference to the treatment of hydrocarbons, and more particularly for the preparation of coal-tar pitch to be used in the manufacture of briquets.

The ends in view are to equalize as far as possible the temperature of all portions of the heated surface, that all parts of the heated mass may be at the same point of distillation; to prevent the coking of the residue locally in consequence of uneven heating, that the product may not be granular and to avoid the choking of the discharge-pipes and the necessity of cleaning the still by scraping after each distillation; to break up the viscous mass within the still, that the throwing off of the volatile matters shall be facilitated; to give the contained mass an agitation of such character that it will break up pockets or imprisoned bodies of gas and vapor which have an explosive tendency when highly heated, and this without giving the mass a rotary motion or carrying the distilled vapors back into the mass; to secure a maximum heating-surface in proportion to the capacity of the still; to secure an increased velocity of the outgoing vapors by restricting the capacity of the still above the evaporating-surface, and, finally, to avoid the clogging of the agitating devices by cold or hardened residue. To this end I construct a horizontal elongated still having in vertical section an extended under surface curved in the arc of a circle of long radius and a top portion contracted, as hereinafter more fully described, and in this still I mount a pendent vibratory agitator.

Referring to the drawings, Figure 1 represents a vertical cross-section of my still on the line 1 1, Fig. 2. Fig. 2 represents a vertical longitudinal section through the center of the still. Fig. 3 is a diagram, on a larger scale, illustrating the sectional form. Fig. 4

is a front elevation of the mechanism for imparting motion to the agitator.

Referring to the drawings, A represents a mason-work furnace, which may be of any suitable construction; B, the still proper, mounted within the furnace, and C the vibratory agitator within the still.

The still consists of a horizontally-elongated body of sheet-steel or other suitable material having, preferably, vertical ends. In cross-section the still is given the peculiar form shown in Figs. 1 and 3, and this general form is of the essence of my invention. The greater part of the under heating-surface or fire-surface is the segment of a circle whose radius is about four-fifths of the diameter of the still. This curve is modified as the sides are approached, or, in other words, toward the lateral limits of the fire-line, an increased or sharper upward curvature being given upward from these points in order that the bearers or supporting-blocks D, which rest in the masonry, may be attached to substantially upright surfaces of the still. The flame and heat from the surface below have access only to the under side of the still. Above the fire-line the still is contracted in diameter, so that its lines fall well within a circumscribing circle. In other words, the still is given a substantially oval form, the base being broadened and flattened and given the greatest possible surface and capacity, while the upper portion is narrowed and contracted, so that the capacity above the level of the material under treatment is materially less than it would be in a still of circular form. This reduction of the space occupied by the released outgoing vapors is of marked importance. The curves may be modified to a limited extent, provided the form and proportions herein shown are approximated. In Fig. 3 the dotted lines indicate the centers from which the various curves are struck.

The agitator C consists of a flat frame E, covered with coarse wire-netting or similar material and firmly attached at its upper edge to the horizontal shaft F, which is seated in a bearing in one end of the still and extended at the opposite end through a gland or stuff-

ing-box. To the outer end of the shaft is secured a crank-arm G, which receives a vibratory motion through a pitman H from a crank-arm I. The shaft of this crank is provided with a worm-wheel J, receiving motion from a worm K on shaft L, provided with a driving-pulley M, connected with an engine or other prime mover. The parts are so proportioned that the rotation of the driving crank I serves to vibrate the agitator C through an arc of eighty degrees, more or less. It will be observed that the shaft F is located in the upper contracted portion of the still, the height of this shaft from the bottom of the still being four-fifths, more or less, of the vertical diameter of the still. The bottom surface of the still throughout the greater portion of its width is described from the axis of the shaft as a center, so that the lower edge of the agitator sweeps over the bottom of the still parallel therewith. The proportions may be modified; but in a still sixteen feet in length and seven feet in height I prefer to leave a space of about four inches between the bottom of the still and the lower edge of the agitator.

The still will be provided at the top with an opening or manhole V and with a pipe U for the delivery of the vapors and also at the rear end with a manhole W and a drainage pipe X.

While the furnace may be modified at will, I prefer to retain the general construction herein shown for the purpose of securing a uniform application of the heat to the bottom of the still.

In the forward part of the furnace there is a fire-chamber N, containing grate-bars O. At the rear end of the grate near the middle of the length of the still there is a bridge-wall P, the upper edge of which has a curve substantially corresponding to that of the under side of the still, so that the gases and heated products passing rearward are distributed uniformly under the still from one side to the other. In order to prevent the direct action of the flame and heat under the middle of the still, an arch or crown R is built above the grate and at some distance below the still, and a series of vertical lateral passages S are extended from the fire-chamber below past the arch into the chamber between it and the still.

A blast-pipe T for the admission of air or superheated steam is extended into the space below the fire-grate, as shown. Doors and chambers of any approved arrangement will be provided to control the combustion. 55

In operating the still it is filled with tar or other material to be treated to a point near the level of the shaft, and fire being maintained the agitator is kept constantly in motion. Its effect is to agitate and break up the mass of contained material, to release the imprisoned vapors, to cause a uniform treatment of all portions of the mass, and to prevent the material from becoming solidified. As the space in the top of the still above the line of the material under treatment is much smaller than usual in proportion to the body of material treated, it follows that the released vapors have a much greater velocity than usual during the outlet, so that there is no danger of their being condensed or redeposited within the still. 60 70

Having thus described my invention, what I claim is— 75

1. A horizontal still of uniform section from end to end, its bottom being curved in the arc of a circle described from a point near the top of the still, and the top being contracted, substantially as shown, in combination with the pendent vibratory agitator, having a horizontal axis near the top of the still. 80

2. The combination of the still proper, having in vertical section a flattened bottom and a contracted top, with the pendent vibratory agitator mounted on a horizontal axis near the top of the still, and the furnace constructed with a fire-chamber, the arch R, therein, and the lateral openings S, for distributing the heat beneath the still. 85 90

3. The horizontally-elongated still B, having the contracted top and flattened bottom curved in the arc of a circle, in combination with the pendent vibratory agitator E, concentric with the bottom of the still. 95

In testimony whereof I hereunto set my hand, this 30th day of March, 1903, in the presence of two attesting witnesses.

FRANCES B. MERRILL.
